UNITED STATES PATENT OFFICE.

EMIL GATHMANN, OF BALTIMORE, MARYLAND.

INGOT MOLD.

Application filed March 5, 1926. Serial No. 92,498.

This invention relates to metal molds of the kind commonly used in casting steel ingots and particularly to molds of the class in which the lower part of the mold walls are made thicker than the upper part thereof and in which the mold cavity is made of larger diameter in the upper portion of the mold than in the lower portion thereof. This is a characteristic of the Gathmann molds now generally in use.

In the casting of metal molds of the kind just referred to, it has been found that better results are obtained when the sand molds in which the metal molds are cast are bottom poured without a cope or cover, the molten metal being caused to rise in the sand mold until the desired size and shape for the ingot mold is obtained. This method of casting ingot molds is so greatly superior to other methods that it has been generally adopted. It has, however, one defect. The upper surface of the casting when formed is quite rough and uneven and in such condition the mold is not suitable for use inasmuch as the top surface of the casting which constitutes the bottom of the ingot mold when in use will not rest properly on the stool or support. This rough surface is caused when direct blast furnace metal is used by what is known as kish and slag, which rises or floats to the upper portion of the sand mold and accumulates on the top of the ingot mold being cast. This kish and other impurities may be raked off to a great extent but the rough surface above referred to remains. The common practice heretofore has been to remove this rough surface by suitable tools or machine-driven implements. This operation, however, adds considerably to the cost of the mold and such costs naturally go into the cost of the ingot and consequently into the costs of the steel. It has also heretofore been proposed to form smooth surfaces on the bottom or base of the mold by chilling portions of the surface whereby it may be made smooth and even so that the mold will be properly supported while being poured.

I have invented a new way of supporting the ingot mold whereby it may be held erect with its longitudinal axis in a true vertical plane and whereby it will be prevented from rocking or tilting when in use. My present improvements are illustrated in the accompanying drawings in which

55 Figure 1 is a view partly in section and

partly in side elevation of a Gathmann ingot mold embodying my invention.

Figure 2 shows a vertical section of a sand mold and appurtenances and indicates how the ingot mold is cast and how the devices 60 for supporting the mold are connected with it.

Figure 3 is a top plan view of the mold illustrated in Figure 2.

Figure 4 is a perspective view of the ingot 65 mold cast in the sand mold.

The ingot mold embodying my improvements is provided with feet which are so formed and so connected with the bottom of the mold that the mold is held erect with the 70 required precision. These feet are separately formed and are connected rigidly with the base of the mold by having their inner or upper portions embedded therein during the process of casting the mold. The 75 outer or bottom faces of the feet are made smooth and even by a chilling operation or in other suitable ways. In this way not only may the mold be properly supported on its stool but clear spaces are provided beneath 80 the mold and on the stool upon which débris such as scale, particles of fire clay, etc., may accumulate and from which they may be easily brushed or raked off.

In Figure 1 a mold of the Gathmann type 85 is indicated at A. It is what is known as a big end up mold having walls thicker in its lower than in its upper portion and the mold cavity is of greater volume at its upper portion than at its lower portion. This type of 90 mold is now generally considered the standard mold for producing steel ingots. The mold is formed with a bottom opening a closed by a plug B and laterally projecting lugs a' are formed at top and bottom of the 95 mold by means of which the mold may be lifted and shifted. As thus far described the mold is of usual construction. A stool for supporting the mold while being poured is indicated at S. In order to support the 100 mold on its stool I employ a plurality of metal feet F. These may be of various shapes but preferably they are tapered as shown, the bottom surface of the feet being rendered smooth and even while the upper 105 portions of the feet are connected with the base of the mold. This connection is made by embedding the upper portions of the feet in the mold bottom in the manner shown and this is effected during the casting of the 110

mold in the way shown in Figures 2 and 3. As there indicated, D indicates a sand mold of well known construction. The sand parts are indicated at d and the flask or frame at d'. The ingot mold cast in the sand mold is shown at A. The sand mold is bottom poured, being supplied with molten metal by a feeding device E of a well-known kind.

During the pouring operation the molten metal rises in the sand mold until it reaches the top thereof and then the pouring operation is discontinued. It will be observed that the upper part of the ingot mold is first formed, that portion of the ingot mold which forms the bottom when in use being the last to be cast. When the pouring has been stopped and during the cooling of the molten metal various impurities accumulate on the top of the mold consisting of what is known as kish and other impurities which float to the top of the mold. Most of these impurities may be brushed or raked off when the metal cools or while cooling, but generally a very rough surface remains which would make the mold wabbly or prevent it from being supported with its vertical axis in a true vertical plane, and as before stated, it has been customary to render the bottom surface of the mold smooth and even by means of suitable tools or machine driven implements, or the difficulties have heretofore been overcome to some extent by forming, during the casting operation, smooth and even surfaces on the mold bottom which can rest on the mold support or stool in such manner that the mold when in use will be properly supported.

According to my present invention, I support the mold on a plurality of feet which are so made and so connected to the mold that the mold is supported with the desired precision in a very simple and effective way. The feet F are preferably tapered as shown and their outer ends are made smooth and even in any suitable way. They are preferably of the same size and shape and may be rapidly and cheaply made by standardized methods. In order to connect these feet with the mold I support a suitable number of them in frames G which are made to rest on the top of the sand mold in the manner shown in Figures 2 and 3. Various kinds of supports may be used; preferably each frame consists of two bars

g placed side by side having curved portions g' to receive the feet and end parts g² which receive rings g³ and wedges g⁴. Each of the frames shown consist of two bars of the kind just described adapted to support two feet. These feet are carefully adjusted in the frames and are clamped therein so that their upper ends shall be in practically the same horizontal plane and when the frames are applied to the sand mold care is taken that the upper end surfaces of the feet shall lie in the same horizontal plane.

As the molten metal rises in the sand mold and approaches the top thereof the inner portions of the feet will be surrounded by the metal and when the pouring operation is stopped it will be found that the feet are firmly embedded in the ingot mold and will project therefrom with their axes in true vertical parallel planes which are also parallel with the axis of the mold. It is desirable that the top of the mold when in use should be smooth and even. Therefore, I employ a chillplate W at the bottom of the sand mold which causes a smooth even surface to be formed on the top of the mold.

It will of course be understood that the sand mold should be so supported that its longitudinal axis will be practically vertical in order that the supporting feet shall be properly connected with the mold in such manner that when the mold is in use it will be properly sustained.

If there should be any tendency for the frames G to be raised or displaced by the molten metal when rising, suitable clamping devices may be used to hold the frames in place.

The mold when complete has a rough surface on the bottom, but the feet hold such surface above the stool or support in the manner before described.

I claim as my invention:

An ingot mold having supporting feet projecting from the lower portion of the mold and the upper portions of which extend into the bottom of the mold and are held therein by the metal of the mold which is cast around their upper ends.

In testimony whereof, I have hereunto subscribed my name.

EMIL GATHMANN.
